UNITED STATES PATENT OFFICE.

HARRY W. HOUCK, OF EAST ORANGE, NEW JERSEY, ASSIGNOR, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

WAVE SIGNALING SYSTEM.

Application filed March 3, 1928. Serial No. 622,521.

This invention relates to improvements in the super heterodyne system of receiving and indirectly amplifying radio frequency electrical oscillatory energy described in U. S. Letters Patent to E. H. Armstrong No. 1,342,885 and it is the object of this invention to provide a highly efficient and stable self heterodyne frequency converting method and apparatus in a super heterodyne system which will enable more reliable reception of signals, particularly radio phone broadcast signals, with a minimum of interference while at the same time enabling a very high degree of selectivity to be secured as between stations operating on but very slightly different wave lengths. Another result achieved by the invention is that reradiation of the locally generated oscillations produced by the self heterodyne is eliminated to the point where it is a negligible factor.

As is well known the super heterodyne system of reception and indirect amplification comprises converting short wave signal energy which cannot efficiently be amplified and received directly, (at least with the present type of vacuum or electron tubes) down to some readily amplifiable intermediate radio frequency which may then be readily amplified, detected and indicated. This frequency conversion is generally accomplished by the heterodyne principle and in U. S. Letters Patent No. 1,342,885 methods and apparatus are described for effecting the conversion by means of both separate and self heterodyne arrangements.

Both the separate heterodyne and the self heterodyne have disadvantages. The separate heterodyne requires the use of at least two vacuum tubes—one an oscillator for producing the local oscillations which are combined with the incoming energy and the other a rectifier which converts or rectifies the combined locally generated and incoming oscillations to produce a third frequency, generally equal to the differences between the local and incoming frequencies; altho a frequency equal to the sum thereof may be obtained.

The normal self heterodyne has the disadvantage that in order to generate the local or heterodyning frequency which in the case of the super heterodyne system should differ from the incoming signal frequency by a third readily amplifiable radio frequency, it must be so far mistuned from the signaling

frequency that the greater part of the otherwise available resonant amplification is lost.

In accordance with the present invention the difficulty arising out of mistuning a self heterodyne system is eliminated for all practical purposes by providing two circuits in the self heterodyne arrangement associated with an electron discharge device or so called vacuum tube having a cathode, an anode and control electrode. One of the circuits so provided may be tuned to the frequency of the incoming signal energy and the other or auxiliary circuit may be tuned to a fundamental frequency which differs by a large amount from the signaling frequency and by a feedback or regenerative circuit arrangement causes the tube or electron device to produce oscillations of the desired fundamental frequency together with harmonics thereof. The fundamental frequency is a sub-multiple of the desired heterodyning frequency preferably so chosen that the frequency of its second harmonic differs from the incoming signal energy by a readily amplifiable third or intermediate radio frequency. Of course, other sub-multiples with other sufficiently strong harmonics may be used and in this event the difference in frequency should also be the readily amplifiable intermediate radio frequency. The harmonic oscillation so generated is then combined with the incoming signal energy oscillation and the combination is then rectified or converted by the self heterodyne tube to produce the readily amplifiable intermediate radio frequency.

The result is an absolutely stable self heterodyne in which an adjustment of either tuned circuit can be made without affecting the other and in which the frequency conversion takes place with equal or better efficiency than with a two tube separate heterodyne arrangement. Further, for all practical purposes the arrangement may be considered non-radiating.

It will be understood by those skilled in the art that while it is possible to have two tuned circuits in a self heterodyne system, one tuned to the incoming signaling frequency and the other to a fundamental frequency differing from the incoming energy by the desired intermediate frequency the arrangement would result in a highly critical organization and in addition would reradiate strongly the locally generated oscillations.

Moreover, such a critical system could not be controlled with success in practice since any change in the tuning of one circuit would produce great reaction on the other circuit and thereby tend to throw the whole system out of adjustment.

Referring now to the drawings and the following description from which a more complete understanding of the invention may be had:

Figure 1 shows a super heterodyne system embodying the invention; and Figure 2 shows a super heterodyne system in accordance with the invention whereby unmodulated continuous wave signals may be indirectly amplified and received.

Referring now to Figure 1; the collector of the incoming signal energy—the antenna system 1—2, which as is well understood may be of any of the well known forms including a loop, is associated by means of the primary 3 with the secondary 4 of the high frequency transformer 5 and the grid-filament circuit 6, 7. The self heterodyne system includes a vacuum or electron tube 8 having a cathode 9, an anode 10, and control electrode 11. Associated with these elements are the tuned circuits 4—12 and 13—14 connected in the grid-cathode or filament circuit 6, 7. The circuit 4—12 is tuned to the frequency of the incoming energy while the circuit 13—14 is preferably tuned to a fundamental frequency equal to one half the frequency of the incoming energy, plus or minus, one half of the desired intermediate or third readily amplifiable frequency. In this way the second harmonic (which is twice the frequency of the fundamental) differs in frequency from the incoming energy by the desired intermediate frequency. It has already been pointed out that other harmonics, if of sufficient amplitude may be employed provided they differ in frequency from the incoming energy by the intermediate frequency which it is desired to produce.

The tuned circuit 13—14, by means of the feed-back circuit 15—16—17 causes the tube 8 with its associated circuits to produce oscillations of the desired fundamental frequency to which the circuit 13—14, is tuned. Because of the fact that the circuit 13—14, is so far mistuned from the frequency of the circuit 4—12, (the frequency of the incoming oscillations) no reaction is produced in circuit 4—12, by the circuit 13—14, or vice versa, if the electrical constants of each are varied in the course of operation. Moreover, with the present arrangement the resonant amplification is retained with a corresponding gain in efficiency.

The incoming energy oscillation and the locally produced harmonic oscillation generated by the tube 8 and its associated circuits are combined in the said circuits and are rectified or converted by the tube 8, to produce the

desired third readily amplifiable intermediate frequency oscillations in the circuit 18—19, in the plate-filament circuit 16—17, of the tube 8 which circuit (18—19) is tuned to the frequency of said intermediate oscillations. 70

The resulting intermediate radio frequency oscillations are then impressed on the input circuit 20—21, of a high frequency amplifier 22 which may be so designed as to amplify most efficiently the particular intermediate 75 frequency which it may be desirable to produce by the self heterodyne arrangement above described. The resulting amplified intermediate frequency oscillations may then be detected and indicated respectively by the 80 tube 23, and the telephones 24, or applied to some other form of indicating device.

In Figure 2 which in all fundamental respects shows a system similar to that of Figure 1, provision is made for the reception of 85 unmodulated continuous waves, that is, the reception of straight continuous wave telegraphy. The operation of the system will be understood from the following explanation:

As in the case of Figure 1 the incoming energy will be collected by the antenna system 30—31, converted by the self heterodyne system 32 and the resulting intermediate frequency oscillations thereby produced amplified by the amplifier 33. The resulting amplified intermediate radio frequency oscillations are then impressed on the input circuit 34—35, of a second self heterodyne system 36, the auxiliary circuits 37—38, thereof being tuned to a fundamental frequency equal to 95 one half the frequency of the intermediate frequency, plus or minus the desired audible beat frequency to be produced in the output circuits 39—40, of the system 36. This, of course, assumes that the second harmonic of 100 the second locally generated oscillation is utilized to interfere with intermediate frequency oscillations and it will be understood in this case that the second harmonic should differ in frequency from the intermediate frequency oscillation by a frequency within the 105 range of audibility and preferably by about one thousand cycles. The rectifying action 110 of the self heterodyne 36 will, therefore, produce in the indicating telephones 41 a beat note of audible frequency.

It will be understood, of course, that the process of frequency transformation and amplification can be repeated with the systems shown in Figures 1 and 2 as many times as desired, as explained in United States Letters Patent No. 1,342,885.

I claim:

1. Apparatus for receiving and amplifying a high frequency oscillatory energy and producing energy corresponding thereto and of lower frequency, comprising an electron discharge device having a cathode, an anode and a control electrode, a tuned circuit associated with said control electrode and deter- 125

- mining the fundamental frequency of said electron discharge device as an oscillator, a second circuit also associated with said control electrode and tuned to the frequency of 5 said high frequency oscillatory energy, a tuned circuit associated with the anode of said electron discharge device, the apparatus having such a degree of feed-back that harmonics of said fundamental frequency will be present 10 in the energy impressed upon said control electrode, one of said harmonics differing from said high frequency oscillatory energy by the frequency to which said tuned circuit associated with the anode is resonant, where- 15 by the rectifying action by which the said harmonic and the high frequency oscillatory energy are caused to produce energy of a low frequency is performed by the same discharge device which produces the harmonic. 20 2. Apparatus for receiving and amplifying a high frequency oscillatory energy and producing energy corresponding thereto and of lower frequency, comprising an electron discharge device having a cathode, an anode 25 and a control electrode, a tuned circuit associated with said control electrode and determining the fundamental frequency of said electron discharge device as an oscillator, a second circuit also associated with said con- 30 trol electrode and tuned to the frequency of said high frequency oscillatory energy, a tuned circuit associated with the anode of said electron discharge device, the apparatus having such a degree of feed back that har- 35 monics of said fundamental frequency will be present in the energy impressed upon said control electrode, one of said harmonics differing from said high frequency oscilla-
- tory energy by a super-audible frequency, the said circuit associated with the anode being 40 tuned to said super-audible frequency, whereby the rectifying action by which the said harmonic and the high frequency oscillatory energy are caused to produce energy of a low frequency is performed by the same 45 discharge device which produces the harmonic.
3. The method of heterodyning a signal by means of a single three-electrode tube which comprises generating by said tube a fundamental and harmonics thereof, one of said harmonics differing from the frequency of 50 said signal by a predetermined frequency, im- pressing the signal on the control electrode of said tube, combining by the rectifying action 55 of said tube the signal and said harmonic to produce therefrom a beat frequency equal to said predetermined frequency and selecting said beat frequency from the frequencies 60 present in the output of said tube.
4. The method of heterodyning a signal by means of a single three-electrode tube which comprises generating by said tube a fundamental and harmonics thereof, one of said harmonics differing from the frequency of 65 said signal by a predetermined super-audible frequency, impressing the signal on the control electrode of said tube, combining by the rectifying action of said tube the signal and said harmonic to produce therefrom a beat 70 frequency equal to said predetermined frequency and selecting and amplifying said beat frequency from the frequencies present in the output of said tube.

In testimony whereof I affix my signature.
HARRY W. HOUCK.
